UNITED STATES PATENT OFFICE.

HENRY L. CHILDRESS AND WALTER B. ROBERTS, OF LYNCHBURG, VIRGINIA, AS
SIGNORS TO DRAPER CORPORATION, OF HOPEDALE, MASSACHUSETTS, A COR-
PORATION OF MAINE.

SHUTTLE-FEELER THREAD PARTER AND CLAMP.

Application filed May 14, 1926. Serial No. 109,073.

This invention relates to shuttle feeler thread parters and clamps for parting and clamping the filling of the outgoing filling carrier or bobbin when replenishment of filling is effected.

It is now the ordinary practice to provide filling replenishing looms with shuttle feeler thread parters and clamps which act upon the filling between the cloth selvage and shuttle to part and clamp the old or outgoing filling end and then carry the clamped portion of such parted filling frontwardly for the action of the temple thread cutter. In some cases the parter and clamp have been mounted upon the shuttle feeler and actuated by the frontward movement of the lay upon call for replenishment of filling and as the shuttle feeler moved rearwardly the parter and clamp have been opened. It has also been proposed to actuate the shuttle feeler thread parter and clamp by means connected to the transferring mechanism, so that on actuation of the transferring mechanism the thread parter and clamp would be operated to part and clamp the filling.

The present invention relates more particularly to this last mentioned type of thread parters and clamps, and one of the objects thereof is to provide a mechanism of this general character which shall be simple in construction and effective in operation. In accordance with the present invention, the thread parter and clamp are mounted upon the shuttle feeler and are connected through a train of mechanism to the transferrer, which, by its downward movement, effects actuation of the parter and clamp when the shuttle feeler is in its rearward feeling position. Such train of mechanism is of rigid character, and to provide for non-actuation or opening movement of the thread parter and clamp as the transferrer moves to its initial position, a novel character of mechanism is provided.

The invention and novel features thereof will best be made clear from the following description and the accompanying drawings of one good form thereof.

In the drawings:

Fig. 1 is a perspective view of portions of a filling replenishing loom provided with the present invention;

Fig. 2 is a cross-section through the breast

beam and lay, showing features of the present invention; and

Fig. 3 is an enlarged detail showing one good form of thread parter and clamp.

The loom frame may be of usual construction and at the filling replenishing side thereof has mounted thereon a magazine or hopper 1 containing filling carriers 2 to be transferred to the shuttle on filling replenishment. The lay 3 is of usual construction, provided with the shuttle box 4 and a transverse recess 5 into which the shuttle feeler may extend when it is moved rearwardly into shuttle feeling position.

Mounted upon the front of the loom, and preferably upon the breast beam 6, Fig. 2, are the brackets 7, one at each side of the loom, having bearings for the transverse or rock shaft 8, from which extends the arm 9, and on the arm 9 is mounted the member 10 providing between the arm 9 and said member the bifurcated end portions for the reception of a pin 11 mounted on the shuttle feeler 12, which is itself preferably supported at 13 on a bracket 14 secured to the loom frame.

Extending upwardly from the bracket 14 is the arm 15 having a thread parter and clamp opener or trip 16, which may be of usual construction and act upon the thread parter and clamp as usual to open the parter and clamp as the shuttle feeler moves rearwardly to its shuttle feeling position.

As shown more particularly in Fig. 3, the shuttle feeler is provided with the thread parting and clamping member 17 which cooperates with a fixed clamping member 18 and the cutting member on the opposite side thereto for parting and clamping the thread. The movable thread parter and clamp 17 is preferably connected to the shuttle feeler 12 at 19, and as such parts may be of usual construction, further description thereof appears unnecessary as they are now well understood in the art.

Mounted upon the dead shaft 20 carried by the magazine or hopper stand is the transferrer 21 having the downwardly extending arm 22 carrying a dog 23 from which projects a pin 24 engaged with a slotted arm 25 connected to the shuttle feeler, the construction being such that upon rocking movement of the rock shaft 8 through the detecting mechanism, as usual, the shuttle

- feeler will be moved from its front to its rear position and the dog 23 will be raised into the path of the usual bunter carried by the lay, so that on forward movement of the lay, 5 the lay the transferrer will be actuated to effect a transfer of the filling from the hopper to the shuttle. All these parts may be of any suitable construction and as usual in looms of this general type.
- 10 Adjustably mounted upon the loom frame is a bracket 26 (Fig. 1) having an outwardly extending arm 27 and provided with bearings 28 in which is supported a rock shaft 29. The rock shaft 29 at its inner end portion has secured thereto a rigid arm 30 to which is pivotally connected at 31 a rod 32, the upper portion of which as shown engages a pin 33 secured to the movable thread parter and clamp 17.
- 15 The center of pivotal motion of the rod or push bar 32 about the pivotal connection 31 is such that the push rod 32 does not effect opening or closing movement of the thread parter and clamp as the shuttle feeler moves 20 to or from the front of the loom.
- 25 Loosely mounted on the rock shaft 29 is an arm 34 which is connected by a rod 35 to the transferrer 21. In the present instance, the transferrer 21 is provided with a 30 pin 36 to which the rod 35 is connected.
- 30 Secured to the rock shaft 29 is an actuator 37 having a shoulder portion 38 extending laterally therefrom in the path of movement of the loose arm 34 which, as described, is 35 connected to the transferrer 21.
- 35 The actuator 37 may be variously contrived as a one-way device and is secured in a rotative adjusted position on the rock shaft 29 by a set screw 39, the purpose being to relate the parts of the actuator to the loose arm 34 that proper actuation of the thread parter and clamp may be effected upon downward movement of the trans- 40 ferrer.
- 45 Since the arm 34 is loosely mounted upon the rock shaft 29, the shoulder portion 38 of the actuator is extended laterally into the path of movement of the arm 34 so that upon downward movement of the transferrer 21, the rod 35 will actuate the loose arm 34 which will thereupon be moved in the direction of the arrow, Fig. 1, and through the shoulder 38 of the actuator cause rock- 45 ing movement of the rock shaft 29 to effect closing movement of the thread parter and clamp, the shuttle feeler at such times being in its rearward shuttle feeling position. As the transferrer 21 moves upwardly to its initial position, it will have no effect upon the rock shaft 29 and the thread parter and clamp will remain closed, with the result that the clamped end of the thread a leading to the cloth selvage will be moved forwardly to position it for the action of the 55 temple thread cutter.

Inasmuch as the amplitude of movement of thread cutters and clamps may be varied, the adjustment of the actuator 37 upon the rock shaft 29 finds convenient and effective means for timing the relation of parts. 70

When the detecting mechanism calls for a replenishment of filling, the rock shaft 8 is turned, thereby moving the shuttle feeler to its rearward feeling position, and through the action of the trip 16 the thread parter and clamp will be opened ready to act upon the outgoing filling end, as usual, and coincidently therewith the dog 23 will be lifted into the path of the bunter carried by the lay and perforce effect downward movement 80 of the transferrer 21. Such downward movement of the transferrer 21 acts through the connection 35 to rock the loose arm 34 of the rock shaft 29, and upon engagement of the loose arm 34 with the shoulder or 85 projection 38 of the actuator which is secured to the rock shaft 29, the arm 30 will be lifted to effect closing movement of the thread parter and clamp. As the transferrer 21 returns to its initial upward position, the 90 arm 34 will have no effect upon the rock shaft 29.

When the shuttle feeler is moved forwardly following replenishment of filling, the thread parter and clamp will remain 95 closed. As the shuttle feeler is moved rearwardly to its shuttle feeling position and the thread parter and clamp are opened by the trip 16, the rock shaft 29 will be rocked contraclockwise to again place the shoulder 100 38 of the actuator into position to be operated by the loose arm 34 upon subsequent downward movement of the transferrer.

From the construction described it will be clear that the present invention provides a 105 simple, effective and positive means connected to the transferrer for actuating the shuttle feeler thread parter and clamp.

What is claimed is:

1. In a filling replenishing loom, the combination of a transferrer, a shuttle feeler having a thread parter and clamp, a rock shaft mounted on the loom frame and connected to the parter and clamp, an arm loosely mounted on the rock shaft and connected to the transferrer, and a one way actuator carried by the rock shaft and moved by said arm on downward movement of the transferrer to close the thread parter and clamp to part and clamp the thread. 110
2. In a filling replenishing loom, the combination of a transferrer, a shuttle feeler having a thread parter and clamp, a rock shaft mounted on the loom frame and connected to the parter and clamp, an arm loosely mounted on the rock shaft, a link connection between the arm and trans- 115 ferrer, and an actuator secured to the rock shaft constructed and arranged to be engaged by the arm on transfer movement of the trans- 120
3. In a filling replenishing loom, the combination of a transferrer, a shuttle feeler having a thread parter and clamp, a rock shaft mounted on the loom frame and connected to the parter and clamp, an arm loosely mounted on the rock shaft, a link connection between the arm and trans- 125 ferrer, and an actuator secured to the rock shaft constructed and arranged to be engaged by the arm on transfer movement of the trans- 130

ferrer to operate the parter and clamp to part and clamp the thread.

3. In a filling replenishing loom, the combination of a transferrer, a shuttle feeler having a thread parter and clamp, a rock shaft having a rearwardly extending rigid arm, a push rod connecting said arm and thread parter and clamp, an arm loosely mounted on the rock shaft and connected to the transferrer, and an actuator secured to the rock shaft and operated by the loose arm on downward movement of the transferrer to close the thread parter and clamp.

4. In a filling replenishing loom, the combination of a transferrer, a shuttle feeler having a thread parter and clamp, a rock shaft mounted on the loom frame and connected to the parter and clamp, a loose connection between the transferrer and rock shaft, an actuator secured to the rock shaft constructed and arranged to be engaged by the loose connection with the transferrer on transfer movement thereof to operate the parter and clamp to part and clamp the thread, and means for adjustably connecting the actuator in different rotative positions on the rock shaft.

5. In a filling replenishing loom, the combination of a transferrer, a shuttle feeler having a thread parter and clamp, a rock shaft mounted on the loom frame and connected to the thread parter and clamp, an arm loosely mounted on the rock shaft and connected to the transferrer for actuation thereby, and an actuator secured to the rock shaft and having a shoulder projecting into the path of movement of the loose arm that the parter and clamp may be operated to part and clamp the thread on downward movement of the transferrer and remain closed as the transferrer returns to initial position.

6. In a filling replenishing loom, the combination of a transferrer, a shuttle feeler

thread parter and clamp thereon, a rock shaft mounted on the loom frame and having an arm extending below and connected to the parter and clamp, an actuator secured to the rock shaft and having a shoulder, an arm loose on the rock shaft adjacent the actuator, and connections between the transferrer and loose arm to move the latter against the actuator shoulder and turn the rock shaft as the transferrer moves downwardly to thereby operate the thread parter and clamp.

7. In a filling replenishing loom, the combination of a transferrer, a shuttle feeler thread parter and clamp thereon, a rock shaft mounted on the loom frame and having an arm extending below and connected to the parter and clamp, an actuator secured to the rock shaft and having a shoulder, an arm loose on the rock shaft adjacent the actuator, connections between the transferrer and loose arm to move the latter against the actuator shoulder and turn the rock shaft as the transferrer moves downwardly to thereby operate the thread parter and clamp, and means for securing the actuator to the rock shaft in different rotative positions.

8. In a filling replenishing loom, the combination of a transferrer, a shuttle feeler having a thread parter and clamp, a rock shaft having an arm, a rod connected to the parter and clamp and pivoted to the arm to turn about a centre without opening or closing the parter and clamp as the shuttle feeler is moved towards or from the front of the loom, an arm mounted for rocking movement on the rock shaft and connected to the transferrer, and an actuator having a part engaged to said arm as the transferrer effects a transfer.

In testimony whereof, we have signed our names to this specification.

HENRY L. CHILDRESS.
